UNITED STATES PATENT OFFICE.

KARL F. SNOW, OF CLEVELAND, OHIO, ASSIGNOR TO THE C. O. BARTLETT & SNOW CO., OF CLEVELAND, OHIO, A CORPORATION OF OHIO.

DRIER.

No. 879,206.

Specification of Letters Patent.

Patented Feb. 18, 1908.

Application filed April 15, 1907. Serial No. 368,213.

To all whom it may concern:

Be it known that I, KARL F. SNOW, a citizen of the United States, resident of Cleveland, county of Cuyahoga, State of Ohio, have invented a new and useful Improvement in Driers, of which the following is a specification, the principle of the invention being herein explained and the best mode in which I have contemplated applying that principle, so as to distinguish it from other inventions.

My invention relates to driers, and particularly to an apparatus of this character in which a plurality of drying drums are employed, the material to be dried and the drying medium being passed through said drums in opposite directions. Said invention consists of means hereinafter fully described and particularly set forth in the claims.

20 The annexed drawings and the following description set forth in detail certain means embodying the invention, such disclosed means constituting but one of various mechanical forms in which the principle of the invention may be used.

25 In said annexed drawings:—Figure 1 represents a side elevation of my invention; Fig. 2 represents a right hand end elevation of the same; and Fig. 3 represents a transverse vertical section of the two drums and connected parts forming important elements of my invention, said section being on an enlarged scale.

30 In the construction of drier which I have shown in the accompanying drawings and shall now describe, I have employed two drums, one disposed within the other, both of which are inclined, the inclination being in opposite directions and the material to be dried, such as coal, rock, etc., and the drying medium being passed through said drums in opposite directions, the direction of movement of the heating medium, which in this case is hot air, being designated by arrows 35 in full lines and the direction of movement of the material to be dried being indicated by arrows in dotted lines.

35 In order most simply to secure the relative arrangement of drums just described, I provide the structure shown in the several figures above described, see particularly Fig. 1. This structure comprises an outer cylindrical drum A, mounted so as to be inclined in one direction, and an auxiliary drum B of con-

ical or substantially conical form mounted 55 within said outer drum, and in axial alignment therewith, the effect of its conical form being to cause its lower wall to incline in a direction opposite to the direction of inclination of said outer cylindrical drum. It will 60 thus be seen that I provide an outer drum that is in effect inclined, Fig. 1, from left to right, and an inner drum inclined from right to left. Said outer drum A has a door a' and is rotated by means of a girth gear D 65 that meshes with the pinion d, the latter being rotated through connected means from the pulley E, all as is shown in Fig. 1. Drum A is rotatably supported by the riding rings C C' which bear upon the rollers c c', respectively. 70

A furnace F is provided having the grate surface f and the fuel and ash doors f', f'', respectively. The feed spout for the material to be dried is shown at H, the same 75 terminating within a chamber h contained within which is one end of a screw conveyer H' or equivalent means terminating at its other end within the inner drum B, whereby the material is fed into said drum and then during the rotation of the latter is gradually fed downwardly through the same to the left as indicated by the dotted arrow. The right hand end of the drum B is closed so that the heating medium from the furnace F can obtain no access to said drum at this end but passes around the same and intermediately 80 of the two drums A and B, entering the inner drum B at its left end, as plainly indicated by the full arrow, leaving said drum B at its 85 right hand end, being drawn therethrough by means of the fan J. A suitable foundation K is provided for the drier, and at the right hand end of the apparatus is disclosed a housing L for the furnace F, the chamber h and other connected elements. The material which is being dried is discharged from the left hand end of the inner drum B into the outer drum A through which it gradually 90 progresses during the rotation of the latter, being discharged from the same from the end a', Fig. 1, into trough a³ containing a screw 95 or equivalent conveyer a⁴ by means of which it is removed from said trough, as will be 100 readily understood.

105 Disposed adjacently to each of the drums A, B is a series of annular rings or bands A' B', respectively, each drum and its re-

lated rings being connected together by means of longitudinally disposed angle irons forming elevators for the drying material, as will be more fully described hereinafter, said angle irons being connected to the rings and normally abutting the inner peripheries of the respective drums, the same, however, not being rigidly fastened to said drums so that contraction and expansion of the connected rings and drums is permitted without undue strain. The angle irons adjacent to the drum A are designated by the reference character *a*, Fig. 3, and those adjacent to the inner drum B by the reference character *b*, and it will be noted that as said drums are rotated as indicated by the arrows, Fig. 3, said angle irons will convey the material from the lower portions of the respective drums to the upper portions thereof where the material will be discharged from the angle irons or elevators while being progressively advanced through said drums. It should be further noted that when said material is dropped from the angle irons or elevators *a* at the top of the drum A it will in falling to the bottom of said drum contact with the exterior surface of the drum B and thus receive an additional drying.

The extended annular space lying between the inner surface of the outer drum, and the outer surface of the inner drum is furthermore sub-divided by longitudinally disposed partitions *A*² into a plurality of segmental compartments, see Fig. 3. By this construction heaping of the material being dried in the lower portion of the outer drum is prevented since such material is divided up between the several compartments in question so as to be in effect passed through a plurality of individual drums in each of which the relatively smaller proportion of such material is independently subjected to the action above described.

Other modes of applying the principle of my invention may be employed instead of the one explained, change being made as regards the means herein disclosed, provided the means stated by any one of the following claims or the equivalent of such stated means be employed.

I therefore particularly point out and distinctly claim as my invention:—

1. In a drier, the combination of a rotary drum; annular rings disposed adjacently thereto; and means adapted to connect said drum and rings, said means permitting relative movement of the latter and said drum during their contraction and expansion.

2. In a drier, the combination of a rotary drum; annular rings disposed interiorly of the latter; and means connected to said rings and normally abutting said drum, so that relative movement of the latter and said rings is permitted during their contraction and expansion.

3. In a drier, the combination of a rotary drum; annular rings disposed interiorly of the latter; and angle irons adapted to lift the material, said angle irons being connected to said rings and normally abutting said drum, so that relative movement of the latter and said rings is permitted during their contraction and expansion. 70

4. In a drier, the combination of a rotary drum; means disposed adjacently to the inner periphery of said drum and adapted to elevate the material; and a plurality of annular rings to which said elevating means are attached. 75

5. In a drier, the combination of two rotary drums inclined in opposite directions; elevators disposed within each of said drums; means secured to said drums respectively and supporting said elevators; and longitudinally disposed partitions dividing the space 80 intermediate of said two drums into compartments. 85

6. In a drier, the combination of two rotary drums inclined in opposite directions and disposed one within the other; elevators 90 disposed adjacently to the inner periphery of each of said drums; means secured to said drums respectively and supporting said elevators; and longitudinally disposed partitions dividing the space intermediate of said 95 two drums into compartments.

7. In a drier, the combination of two rotary drums inclined in opposite directions and disposed one within the other; angle irons longitudinally disposed adjacently to 100 the inner periphery of each of said drums; a plurality of annular rings contained within each of said drums, said angle irons being attached to said rings, and a plurality of longitudinally disposed partitions dividing the 105 annular space intermediate of said two drums into segmental compartments.

8. In a drier, the combination with an outer inclined substantially cylindrical drum, of a second drum of substantially conical 110 form axially mounted within said outer drum, the lower wall of said inner drum inclining in a direction opposite to that of said outer drum.

9. In a drier, the combination with an 115 outer inclined substantially cylindrical drum, a second drum of substantially conical form axially mounted within said outer drum, the lower wall of said inner drum inclining in a direction opposite to that of said outer drum, 120 means for rotating said drums, and means for conveying the material and drying medium through said drums in series.

10. In a drier, the combination with an outer inclined substantially cylindrical drum, 125 a second drum of substantially conical form axially mounted within said outer drum, the lower wall of said inner drum inclining in a direction opposite to that of said outer drum, means for rotating said drums, and longitu- 130

dinally disposed partitions dividing the annular space intermediate of said drums into segmental compartments.

11. In a drier, the combination with an outer inclined substantially cylindrical drum, a second drum of substantially conical form axially mounted within said outer drum, the lower wall of said inner drum inclining in a direction opposite to that of said outer drum, means for rotating said drums, longitudi-

nally disposed partitions dividing the annular space intermediate of said drums into segmental compartments and means for conveying the material and drying medium through said drums in series.

15

Signed by me this 11th day of April, 1907.
KARL F. SNOW.
